CLAIM

The ornamental design for a toy house as shown and described.

DESCRIPTION

FIG. 1 is a perspective view of the front, top, and right side of a toy house showing my new design;

FIG. 2 is a perspective view of the rear, top, and left side thereof;

FIG. 3 is a front view thereof;

FIG. 4 is a rear view thereof;

FIG. 5 is a top view thereof;

FIG. 6 is a right side view thereof; and,

FIG. 7 is a left side view thereof.

The broken lines shown are included for the purpose of illustrating portions of the article which form no part of the claimed design.

1 Claim, 7 Drawing Sheets
